DIAPHRAGM LEVER AND SADDLE
MECHANISM

Harry C. Wasson, Franklin, Pa., assignor to Chicago Pneumatic Tool Company, New York, N. Y., a corporation of New Jersey

Application May 27, 1931, Serial No. 540,491

1 Claim. (Cl. 137—156)

This invention relates to fluid pressure control apparatus generally and more particularly to that type or portion of such apparatus which transmits pressure into motion. It has direct application to lever and saddle structures for actuation by a diaphragm.

In supporting a knife edge on a diaphragm to actuate a lever, it has been customary to place the knife edge upon and above the saddle, the latter being disposed upon the side of the diaphragm opposite to that upon which the pressure acts. The knife edge actuated by the diaphragm is spaced from the pivot for the lever, so that when pressure forces the diaphragm toward the lever there is a decided tendency for the diaphragm to cock or be tipped instead of to move exactly at right angles to the original position of the lever. The cocking tendency is increased by the flexibility or elasticity of the diaphragm and is still further intensified when the diaphragm is not uniform in strength or section. Thus the flexibility of the diaphragm and changing of direction of the force acting on the diaphragm as the lever rises cause the diaphragm saddle to shift its position due to horizontal components and in so doing rubbing or friction results in the saddle guides which are used to counteract such a tendency. Frequently the diaphragm is caused to buckle since the saddle is usually secured thereto. In either case free movement of the diaphragm is restricted and the sensitiveness of the control apparatus is greatly impaired, if not destroyed. By reason of the many factors involved, it is a practical impossibility to construct a series of units to a standard of sensitiveness and having uniform control characteristics.

Among the objects of the invention are to secure free action, sensitiveness, and uniform operation in control devices involving diaphragm and lever arrangements, and in general to improve prior arrangements in the interests of more efficient and satisfactory service.

In the present invention an underslung arrangement is provided in which a yoke or loop carrying the knife edge engaging the lever depends directly from the saddle. The latter preferably has a flat lower face resting upon the diaphragm. With this construction the center of pressure is always maintained in the same general direction and there is little or no tendency to cock or displace the diaphragm saddle. Hence guides for the saddle may be dispensed with, resulting in free action and sensitive operation. The yoke is by preference rigidly secured to the

saddle so that any tendency of the knife edge to creep along the lever is obviated.

In order to illustrate the invention one concrete embodiment thereof is shown in the accompanying drawing, in which:

Fig. 1 is a side elevational view partly in section on the line 1—1 of Fig. 2; and

Fig. 2 is an elevational view from the right side of Fig. 1 and partly in section on the line 2—2 of Fig. 1.

The embodiment of the invention chosen for the purpose of illustration comprises control mechanism for variably regulating the operation of an air or gas compressor or pump (not shown). The apparatus is secured to a suitable support, 70 indicated at A, which may be a part of the compressor frame. Upon support A rests a casing 3 having an opening at one side through which extends a lever 4 supporting weights 5 at its outer end. A thick metal plate or cover 6 is secured 75 to the top of casing 3 and upon cover 6 rests a smaller casing 7. Bolts 8 secure casing 7 and cover 6 to lower casing 3 and serve securely to clamp the peripheral portions of a diaphragm 9 between cover 6 and casing 7, the diaphragm extending across the chamber formed by said last named elements. A pipe or conduit 10 leads from the air receiver (not shown) of the compressor and communicates with a passage 11 in cover plate 6 which opens into a central depression 6a in the cover plate beneath diaphragm 9. A saddle 12 is disposed within casing 7 to rest upon the upper face of diaphragm 9 and is of a size to provide ample clearance between itself and the walls of casing 7 thereby to avoid any 90 frictional resistance through contact as the saddle is lifted as a result of pressure released beneath diaphragm 9. Movement of saddle 12 is transmitted to lever 4 by a suitable connection which will presently be described. The movement of lever 4 is transmitted by a rod 4a to fluid pressure governing or regulating apparatus of any suitable or desired type indicated generally at B which may be secured at any suitable point as to the top of casing 7. The particular 100 governing apparatus shown is of the Mason regulator type and is fully disclosed and claimed in copending application of Lester L. Collins, Serial No. 356,695, filed April 20, 1929. Since the regulating or governing apparatus used with my diaphragm and lever mechanism forms no part of the present invention, further description thereof is omitted.

A pivotal abutment for lever 4 is provided by spaced members 13 depending from cover plate 6. 110

Lever 4 extends between members 13 and is provided with a cross piece 4b with upwardly extending knife edges 4c engaging the lower faces of members 13 to serve as a pivot. A rigid frame, indicated generally at 14, provides an underslung connection between saddle 12 and lever 4. Frame 14 comprises a transverse or horizontally disposed top cross piece 14a which extends through openings 7a (Fig. 1) in casing 7. It rests directly upon saddle 12 and is rigidly secured thereto by suitable means such as one or more machine screws 15. Parallel side members 14b interfit with and depend from upper cross piece 14a and are rigidly secured to the latter in any suitable manner as by cap screws. Similar screws and an interfitting connection secure in a rigid manner a lower cross piece 14c to the side members, the lower cross member extending through openings in lower casing 3. Lower cross member 14c carries on its upper face a knife edge projection 14d which engages the under face of lever 4 at a contact point 4d slightly spaced from pivot contact 4c.

The central point of saddle 12 to which frame 14 is secured is in vertical line with contact point 4d. Hence, the upward pull of frame 14 on lever 4 as saddle 12 is forced upwardly by the expansion of diaphragm 9 under fluid pressure admitted by conduit 10 is in a straight line and any tendency to deviation therefrom is effectively counteracted by the underslung connection and the straight line pull. By preference saddle 12 is made with a flat lower face, as shown, in con-

tact with diaphragm 9. There is no frictional resistance to the upward movement of saddle 12 since saddle 12 and frame 14 are at all points and at all times out of contact with stationary portions of the mechanism. Hence the present invention provides a self-aligning device without guides of any character for transmitting, without friction, to a weighted lever a force applied by fluid pressure under a diaphragm.

While the invention has been herein disclosed in what is now considered to be a preferred form, it is to be understood that the invention is not limited to the specific details thereof but covers all changes, modifications, and adaptations within the scope of the appended claim.

I claim as my invention:

In control apparatus having a pivotal lever and fluid pressure means acting upon said lever through a contact point adjacent said pivot for moving said lever against gravity, a diaphragm disposed above said lever and having its lower face subjected to fluid pressure, a saddle in loose engagement directly with the upper face of said diaphragm, a casing for supporting said diaphragm, said casing having a portion closely surrounding the saddle but out of frictional contact with the latter, horizontal arms rigidly secured to the upper surface of said saddle and projecting laterally through recesses in the casing, and depending means rigidly secured to said arms providing an underslung connection between said saddle and said point of contact.
